Elmir J. Noy. of Lowell. Mass.

Assignor to

The Lowell Manufacturing Company.

Letters Patent No. 1120. Dated July 5, 1859.

C.

The schedule referred to in these Letters Patent, and making part of the same.

To all whom it may concern:

It is known that J. Elmir J. Noy. of Lowell in the County of Middlesex, and State of Massachusetts, have originated and designed a new pattern for Carpets or other fabrics, of which the following is a full, clear and exact description, reference being had to the accompanying drawings, making part of this specification.

The four corners "A", when matched, form a center covered with dots running diagonally, the whole surrounded by tree work; the center "B", consists of a group of fruit, flowers and leaves resting on a plain ground; between the center "B" and the corners "A", run branches "C", covered with foliage "D", said branches forming by their intersections, four small centers "E", covered with dots, surrounding the center "B" and occupying the space between the corners "A".
